GRID CONTROLLED ELECTRON TUBES

Theodore White Small, Phoenixville, Pa., assignor to Philco Corporation, Philadelphia, Pa., a corporation of Pennsylvania

Application December 2, 1953, Serial No. 395,771

11 Claims. (Cl. 313—248)

This invention relates to electron tubes and more especially to tubes having one or more grid electrodes.

A principal object of the invention is to provide an improved grid electrode structure for electron tubes.

Another object is to provide a novel grid electrode structure and lead-in which is particularly advantageous in tubes for use in high frequency circuits.

A further object relates to improvements in grid controlled tubes for use in grounded grid amplifiers, oscillators, and the like.

A feature of the invention relates to an electron tube having a wire wound grid of highly rugged construction and wherein the grid laterals can be made parallel to each other to form a so-called flat grid, without requiring special presetting of the grid turns.

Another feature relates to a wire wound grid electrode wherein the fine wires or turns of the grid are supported on a double-windowed cylindrical frame whereby the finished grid is extremely rigid.

Another feature relates to a unitary grid frame and lead-in element whereby the grid lead-in inductance is reduced as compared with the conventional lead-in construction, and the finished grid unit is of highly rugged character.

A further feature relates to a grid-controlled electron tube wherein the undesirable characteristics of the conventional grid side rods are reduced to a minimum.

A further feature relates to a novel grid electrode structure for electron tubes whereby greater mutual conductance can be obtained.

A further feature relates to a novel glass stem and sealed in grid frame unit of cylindrical contour which enables the grid frame itself to be used as a rigid winding mandrel for the fine wire wound grid laterals.

A still further feature relates to the novel organization, arrangement, and relative location and interconnection of parts which cooperate to provide an improved rugged high frequency electron tube.

Other features and advantages not particularly enumerated will be apparent after a consideration of the following detailed descriptions and the appended claims.

In the drawing which illustrates the invention in certain of its preferred forms.

Fig. 1 is a perspective view of an electron tube embodying the invention.

Fig. 2 is a sectional view of Fig. 1, taken along the line 2—2 thereof.

Fig. 3 is a sectional view of Fig. 1, taken along the line 3—3 thereof.

Fig. 4 is a sectional view of Fig. 3, taken along the line 4—4 thereof.

Fig. 5 is a sectional view of Fig. 3, taken along the line 5—5 thereof.

Fig. 6 is an exploded view of the novel electrode spacers according to the invention to explain their manner of assembly in the electrode mount.

Fig. 7 is a perspective view of the grid frame and grid lead-in element according to the invention.

Fig. 8 is a schematic plan view of a conventional tube of the elliptical grid kind, referred to in explaining certain advantages of the invention.

Fig. 9 is a view of a modified elliptical grid tube employing certain features of the invention.

Fig. 10 is a schematic plan view of a conventional tube of the circular grid type referred to in explaining certain advantages of the invention.

Fig. 11 is a schematic plan view of a circular grid tube embodying certain features of the invention.

Fig. 12 is a schematic plan view of a conventional flat grid, flat cathode tube referred to in explaining certain features of the invention.

Fig. 13 is a schematic plan view of a flat cathode, flat grid tube embodying features of the invention.

Fig. 14 is a schematic plan view of a modification of the invention.

Referring to Figs. 1—6, the numeral 10 represents a header of glass, ceramic or other similar insulating material through which the lead-in members for the various electrodes and elements of the tube mount, are sealed in a vacuum-tight manner. The header 10 serves as the base or support for the various elements of the mount which, for simplicity in the drawing, is shown as of the triode kind having a central electron-emitting cathode 11 which may be a cylindrical or rectangular shaped cathode sleeve with its usual internal insulated heater element (not shown), a grid electrode 12, and a plate or anode electrode comprising for example oppositely arranged rectangular channel shaped metal sheets 13, 14, electrically connected by a metal strap (not shown) to join them electrically. The electrode mount is enclosed by a suitable bulb 15 which is sealed in a vacuum-tight manner to the rim or edge of the header 10.

In accordance with one feature of the invention, the mount is assembled to form a rugged unit and is supported on the grid lead-in member 16 which is in the form of a cylindrical metal tube sealed centrally through the glass header 10 by any well-known sealing technique, so as to have portions projecting exteriorly and interiorly of the tube. Member 16 extends upwardly interiorly of bulb 15 and the walls of this upwardly extending portion are cut out to provide substantially semi-cylindrical opposite windows 17, 18, while leaving the uncut portions 19, 20, to form rigid diametrically opposite metal uprights around which the fine wire 21 can be wound, for example as a plural-turn helix. Thus, the wire 21 forms a wire wound grid wherein the grid laterals on one side of the cathode 11 are in the same flat plane and the grid laterals on the opposite side of the cathode 11 are also in a flat plane, both planes being parallel to each other.

The spacing of these grid laterals from the cathode is determined by the width of the portions 19, 20 of the grid lead-in and support member 16, and the desired flatness and parallelism of the two sides of the grid can be achieved without subjecting the grid wires to a special flattening operation which may be necessary when conventional grid side rod supports of round cross section are employed, and as will be explained hereinbelow in connection with Figs. 8 through 13.

Thus, the members 19, 20, not only serve as the usual rigid side supports for the fine wire wound grid but they also predetermine the spacing of the opposed grid laterals. It is highly important to certain types of tubes to have the grid as close as possible to the cathode but without danger of the grid laterals touching the cathode. The structure shown in Figs. 1 to 6, enables this result to be obtained by a simple winding operation of the fine grid wire around the novel grid frame support, and the width of the portions 19, 20, can be made any desired size to determine the spacing of the grid laterals with respect

to the cathode. I have found that with this method of winding and supporting the grid wire it is not necessary to subject it to exceptional tensioning during the winding operation as would be the case with conventional round grid side rod supports.

In accordance with another feature of the invention and as a result of the construction of member 16, I have found that extremely fine wire can be used for the grid turns and it is possible to hold the adjacent turns in their original wound spacing by subjecting the member 16 where the grid turns are wound thereon to a silver plating operation. This silver plating provides sufficient anchorage of the fine wire to the members 19 and 20, and avoids the conventional and costly operations of welding or peening the fine wire grid turns to their respective side rods. However, prior to plating the turns in place on members 19 and 20, the extreme ends of the wound wire can be anchored to the members 19 and 20 by a suitable cement such for example as amyl acetate or polystyrene.

For the purpose of holding the cathode and plate electrodes in proper spaced relation to the grid, a conventional top mica disc 22 may be used, having a central opening to receive the upper end 23 of the cathode. When the cathode sleeve 11 is rectangular in cross-section as illustrated in the drawing, the mica disc 22 has a corresponding centrally located rectangular opening through which closely fits the projecting end of the cathode sleeve. Of course, if the cathode sleeve 11 is circular in cross-section, the central opening in the mica disc 22 would be circular in shape. Likewise, the upper edges of grid member 16 has a pair of integral lugs 24, 25, which project through corresponding openings in the top mica 22. Similarly, the upper edges of the plates 13 and 14 have integral lugs 26, 27, 28, 29, which project through corresponding openings in the mica 22 and these lugs are bent back to anchor the said plates against the mica 22. For the purpose of anchoring the lower end of the cathode and plate elements there are provided two substantially T-shaped mica members 30, 31, each having a central narrow lug 32, 33, and a cross lug 34, 35. The mica 30 is assembled with the leg portion 32 extending through the windowed portions 17 and 18 of the grid lead-in and grid frame unit 16. The leg portion 32 has a pair of slots 36, 37, which are adapted to fit over and receive integral lugs 38, 39, on the grid frame. In the case of a rectangular cathode sleeve, the leg 32 also has a rectangular slot 40 to receive the lower end 41 of the cathode. The mica spacer 31 is then assembled in place with its leg 33 overlying the leg 32 of member 30. The leg 33 has slots 42, similar to slots 36 and 37 to receive the lugs 38 and 39. Leg 33 also has a round opening 43 through which passes the lower end of cathode 11. However, the diameter of hole 43 should be greater than the maximum dimension of hole 40. In other words the cathode sleeve is supported only by the lower mica 30, and it passes freely through the hole 43 in mica 31. If the cathode sleeve 11 is circular in cross-section, then the cathode holes in all the micas 22, 30 and 31, will be circular in shape to fit the cathode sleeve. Preferably, the cylindrical lower portion of member 16 is undercut as indicated by the numerals 38A, 38B, so as to provide clear spaces or windows beneath the mica 31 and through which may freely pass the cathode connection tab 11a and the cathode heater wire ends 11b. When the two mica members 30 and 31 have thus been assembled the lugs 38 and 39 are bent outwardly to anchor the said micas in place. The mica members 30, 31, also have openings 44, 45, 46, 47, to receive corresponding integral lugs on the lower edges of plates 13 and 14 and these lugs can be bent outwardly to anchor the said plates to the micas 30 and 31.

After the mount has been assembled the connections between the cathode heater element (not shown) and its lead-in members, for example lead-in members 48,

49, can be made. Likewise, a suitable connection between the plates 13, 14, and the respective lead-in member, for example member 50, may also be made. The lead-in for the grid electrode is of course provided by the externally projecting portion of the member 16. The member 16, because of its large diameter, provides a more efficient coupling to a high frequency circuit. For example, it can be telescoped in spaced relation over the tubular conductor 51 whereby the grid can be capacitively coupled into a suitable circuit. This large diameter lead-in for the grid also reduces the effective self-inductance of the said lead-in, as compared with the conventional lead-in wire or prong.

The manner of assembling of the various elements 15 of the mount will be clear from the foregoing. However, one of the important novel features of the invention is that the grid element 16 when sealed into the glass header 10 can be used directly as a winding mandrel for the fine wire grid 21. Thus, the header 10 with the sealed- 20 in member 16, can be fastened in a suitable rotating chuck and the wire 21 can be wound around the members 19 and 20 by using the member 16 itself as the winding mandrel. This is possible because the elements 19 and 20 form a highly rigid unit with the cylindrical or non-windowed portions of member 16. Heretofore, in winding conventional grids employing conventional side rods the said side rods must be assembled in a suitable arbor which must be accurately machined and designed to enable the wound grid to be removed therefrom after the winding is completed. All that is necessary according to the present invention, is to support the header 10 with its sealed-in element 16 in a rotatable chuck. One end of the fine wire 21 can then be cemented, for example to the outer face of member 19 25 adjacent one end thereof and the said wire 21 can then be given the desired lead as it is being wound. When the desired number of turns have been wound, the last turn can be cemented to the appropriate member 19 or 20 and then severed. The unit consisting of elements 30 35 10, 16 and 21, can then be removed from the winding chuck and the turns of the winding 21 can be permanently fastened in place by subjecting the members 18 40 and 19 and the wire 21 where it contacts the said members 19 and 20 to a suitable plating operation, such for 45 example as silver plating.

After the grid turns have thus been anchored in place on members 19 and 20, the mica element 30 is assembled as above described whereupon the lugs 38 and 39 are bent outwardly. The cathode 11 can then be inserted 50 with its lower flattened end projecting through the mica 30 and this projecting end can be provided with the usual connection tab 11a. The plate elements 13 and 14 can then be assembled in place and the lugs on their lower edges bent back to anchor them to the micas 30 55 and 31. The top mica 22 may then be assembled in place and the corresponding lugs 24, 25, and 26—29, bent to anchor the top mica in place.

Apart from the fact that the structure as hereinabove described provides a highly rugged tube mount, is the 60 fact that the grid construction as described produces electrical characteristics which are also of great importance, particularly in high frequency and ultra high frequency circuits. The invention enables the tube to be used with a grounded grid in ultra high frequency circuits 65 while obtaining low lead-in inductance.

Furthermore, the unit consisting of the header 10 and the elements 16 and 21 is in itself extremely rugged because of the strength of the cylindrical tubing from which the element 16 is made. This unit can then be handled 70 in large quantities without too much danger of the grid turns being distorted with respect to the rest of the grid. Furthermore, it is possible to handle the unit without touching the grid turns themselves since the unit can be handled by means of the glass header 10, thus reducing 75 the chance of contaminating contact with the grid turns.

Furthermore, because of the particular structure, when the unit consisting of elements 10, 16 and 21 is placed in a tray or other carrier, the wound length of the grid 21 always remains out of contact with the surface of the carrier, thus further reducing the likelihood of deformation, or contact contamination of the grid turns.

It will be understood, of course, that the invention is not necessarily limited to a grid of the wire wound type. For example, as shown in Fig. 14, the grid frame 16 can have sheets of fine wire mesh attached to the edges of the members 19 and 20 and fastened thereto by plating.

While Figs. 1 through 7, and Fig. 14, relate to a tube of the so-called flat grid type, the invention has advantages in tubes wherein the grids are elliptical, circular or other shape. In Fig. 8 there is shown in schematic plan view, the cathode and grid and anode of a typical conventional tube wherein the central cathode 54 is surrounded by elliptical wound grid 55 which is welded or otherwise attached to the conventional round grid side rods 56, 57. This grid is then surrounded by a tubular plate or anode 58. The side rods 56 and 57 have substantial thickness considered radially with respect to the cathode 54 so that when they are negatively polarized they cast both a physical and an electric shadow on the plate 58 as represented by the shaded portions 59 and 60. On the other hand, and as shown in Fig. 9, by using a grid frame and lead-in construction, such as illustrated in Fig. 7, the members 19, 20, have very little thickness considered radially of the cathode 54. Furthermore, for a given mechanical strength, it is possible to make the width of the members 19 and 20 relatively small so that the physical and electron shadow on the anode 58 can be made much smaller.

Furthermore, in certain types of tube construction it is possible, because of the reduced radial thickness of the members 19 and 20, as compared with the conventional round side rods, to bring the grid turns closer to the cathode without corresponding liability of short-circuiting between the cathode and grid. For example, as shown in Fig. 10, with the conventional round side rod construction, the minimum spacing between the grid turns and the cathode is limited by the radial thickness of the grid side rods, whereas in the embodiment of Fig. 11 using a grid frame such as element 16 the relatively small radial thickness of the members 19 and 20 enables the grid wire to be brought substantially closer to the cathode.

A further advantage of the invention as applied to flat type grids is that it avoids the step of forming or setting the grid laterals in order to achieve the necessary parallelism between a flat type cathode. Thus, there is shown in Fig. 12, a conventional tube structure employing a flat cathode 61 which is surrounded by a fine wire grid 60, this grid being attached to and supported on conventional round side rods 63, 64. Because of the springiness of the usual grid wire 62, it has been found that in certain types of tubes it is necessary to deform or bend the wires inwardly, as indicated at 65, in order to preserve the necessary parallelism between the remaining length 66 and the flat faces of the cathode 61. This grid-forming operation has been found to be comparatively expensive and difficult of control. As shown in Fig. 13, by employing a grid frame such as the element 16 with the integral support members 19 and 20, the winding of the fine grid wire 21 therearound automatically maintains the desired parallelism with the flat type cathode 61.

While the invention is not limited to any particular materials, it will be understood that the member 16, or at least that portion of it which is in contact with the glass header 10, is of a metal or alloy having substantially the same expansion coefficient as the glass of the header.

Various changes and modifications may be made in the disclosed embodiments without departing from the spirit and scope of the invention.

What is claimed is:

5. 1. An electron tube mount comprising a tubular metal grid frame having a pair of oppositely disposed cutout windows defining a pair of oppositely disposed integral ribs, a pair of insulator spacer members each inserted respectively through said windows, said spacer members 10 extending internally across the tubular member and anchored thereto, each of said insulator spacer members when superposed having aligned openings located at the center of said tubular member to receive one end of a cathode electrode.
15. 2. An electron tube mount according to claim 1, in which the lower edge of each of said windows has an integral tab, and each of said spacer members has a pair of openings in interlocked engagement with said tabs.
20. 3. A grid electrode for electron tubes comprising a tubular metal member having oppositely disposed cutout windows defining a pair of remaining integral ribs, and a foraminous grid element extending transversely between said ribs and anchored thereto and forming with said ribs a tubular discharge chamber whose outer boundary 25 is well within the outer boundary of said tubular metal member.
25. 4. A grid electrode according to claim 3, in which metal plating means anchors said foraminous grid element to said ribs.
30. 5. A grid electrode for electron tubes comprising a tubular metal member having oppositely disposed cutouts defining a pair of windows with the remaining uncut part defining a pair of integral oppositely disposed ribs, each of said ribs having a width which is only a small fraction of the peripheral dimension of said member, and a grid wire wound around said ribs and extending transversely to the rib length and having the turns thereof anchored to said ribs and forming with said ribs a tubular discharge chamber whose outer boundary is well within the outer boundary of said tubular metal member.
35. 6. An electron tube, comprising an enclosing envelope, a unitary tubular metal member sealed vacuum-tight through the wall of the envelope and having one portion 40 projecting externally thereof to constitute a lead-in member, and another portion extending internally of the envelope to constitute a rigid electrode mount support, said mount including a cathode, a grid, and an anode, and insulator spacer means insulatingly spacing the cathode, grid and anode from each other, and means comprising the said internally projecting portion of said tubular member for supporting said cathode, grid and anode therefrom as a unit.
45. 7. An electron discharge tube comprising, an enclosing envelope, said envelope enclosing a plurality of cooperating electrodes one of which defines a tubular discharge chamber; said chamber comprising a tubular metal member sealed vacuum-tight through a wall of said envelope and having a portion extending interiorly of the envelope 50 and a portion extending exteriorly of the envelope, said interiorly extending portion having oppositely disposed windows defined by a pair of oppositely disposed ribs forming an integral part of said tubular member and foraminous conductive means extending across each window and fastened to said ribs, said foraminous means being located within the boundary defined by the periphery of said tubular member.
55. 8. An electric discharge device according to claim 7, in which said tubular member is cylindrical and said foraminous means is in the form of a fine wire wound around said ribs so as to form said oppositely disposed walls which are substantially planar and parallel.
60. 9. An electric discharge device according to claim 7, in which said tubular member is cylindrical and said foraminous means is in the form of a fine wire wound 65
70. 75. 10. An electric discharge device according to claim 7, in which said tubular member is cylindrical and said foraminous means is in the form of a fine wire wound

around said ribs so as to form said oppositely disposed walls which are arcuate.

10. An electron tube mount unit according to claim 7, in which a pair of insulator spacer members are provided each having a portion inserted through said windows and anchored to said tubular member, each of said spacer members also having a portion extending radially outward from said tubular member, and at least one other electrode anchored to said insulator members.

11. An electron tube mount unit according to claim 7, in which an electron-emitting cathode is located centrally within said tubular metal member and an anode electrode is arranged in spaced relation to the outside of said cylindrical metal member, and means interlocking said tubular member, said cathode and said anode as a unit 15 and including a pair of insulator spacer members each having a portion inserted through said windows and inter-

locked with said tubular metal member, each of said insulator spacer members having aligned openings located inside said tubular member receiving and anchoring one end of said cathode, each of said insulator spacer members having a portion extending radially away from said tubular metal member and having means interlocking said spacer members with said anode electrode.
